GRIPPING TOOL

John B. Zimdars, San Francisco, Calif.

Application October 12, 1942, Serial No. 461,805

13 Claims. (Cl. 81—151)

This invention relates to gripping tools and particularly to hand tools, such as wrenches, pliers, and the like.

The primary object of the invention is to provide a manipulating mechanism for quickly adjusting the jaws of a gripping tool approximately to the outside dimensions of an object to be gripped, and then by quick and positive action to firmly engage the jaws of the tool with said object and lock said jaws in such a manner that the jaws cannot be pried apart by the usual forces applied in manipulating the objects worked on; means being provided for quickly disengaging the jaws from the work at will.

Particularly, it is an object of this invention to provide a manipulating mechanism for relatively moving the jaws of a gripping tool without tedious adjustment by screws or the like, and to simultaneously lock the jaws in said adjusted positions.

Another object of this invention is to provide a controlling mechanism for the jaws of gripping tools which is highly useful and simple in construction. Convenience of arrangement, lightness and comparative inexpensive of manufacture are further objects which have been borne in mind in the production and development of the invention.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawing.

With the foregoing and other objects in view, which will be made manifest in the following detailed description, reference is had to the accompanying drawing for the illustrative embodiment of the invention, wherein:

Fig. 1 is a partly sectional view of a wrench showing my jaw control mechanism.

Fig. 2 is a fragmental edge view of said wrench.

Fig. 3 is a partly sectional edge view of the wrench viewing from the side of the fixed jaw.

Fig. 4 is a partly sectional and fragmental view of the wrench, showing the jaws and the jaw control mechanism in gripping position.

In carrying out my invention in connection

with the type of wrench herein, the opening between the jaws is adjusted in a direction at right angles to the longitudinal axis of the wrench handle. In the herein illustration, this wrench is made of a pair of complementary half-sections 11 which are longitudinally held together by suitable rivets 12, or screws, or other securing elements. A suitable hole 13 is provided in the end of the handle 14 for the purpose of hanging the tool. In the herein illustration the handle 14 is suitably recessed on the opposite sides for improving the hand grip and reducing the weight of the tool. In the first illustrative embodiment herein, the gripping ends of the half sections 11 are formed in the shape of a fixed jaw 16 with a gripping face 17 substantially parallel with the longitudinal axis of the tool. In some tools the gripping faces may be at desired angles to the axis of the handle. It is to be noted that a tongue 15 and groove connection 18 is provided between the opposite halves of the jaw 16 for assuring uniform and positive alignment of the superposed sections. Each of the half sections 11 is provided with a guide recess 18 immediately beneath the gripping jaw 16 so as to provide a passage for a movable guide block 19. The top of this guide passage 18 is substantially at right angles to the longitudinal axis of the tool and the lower wall of the guide passage 18 is tapered outwardly and away from the jaw head of said sections. Each of these guide recesses 18 has a horizontal guide rail 21 formed thereon. The guide block 19 has a horizontal top slidably engaged with the top of the passage formed by the guide recesses 18 and a tapered lower edge 22 riding over the inclined lower walls of the guide recesses 18. The guide block 19 has grooves 23 on its opposite sides slidably engaged with the respective guide rails 21 in the guide recesses 18. On the top of the guide block 19 and at the end farthest from the fixed jaw 16, is provided another gripping jaw 24, which latter is substantially of the same shape as the fixed jaw 16 and has a gripping face 25 opposite to and parallel with the gripping face 17 of the fixed jaw 16. The position of the gripping jaw 24 is adjusted by moving the guide block 19 in the recesses 18 toward and away from the fixed jaw 16, in accordance with the adjustment required. The outward movement of the guide block 19 away from the fixed jaw 16 is limited by an abutment 27, which is formed by one of the securing rivets or screws used for securing the half sections 11 together. The guide block 19 is provided with an end slot 28 which fits over the abutment 27.

The half sections 11 are so recessed on the inside faces thereof as to provide a cavity 29 between the gripping end of the tool and the top of the tool handle portion. This cavity 29 is closed at one longitudinal edge by complementary longitudinal flanges 31, and at the other edge by massive flanges 32 which on their outside contour taper to the outer curvature of the fixed jaw 16. Into this cavity 29 is placed the manipulating and locking mechanism for the adjustment of the guide block 19 and movable jaw 24. A lever 33 extends through an opening 34 at the lower end of the cavity 29 and alongside the longitudinal flanges 31. The free end of the lever 33 is inserted in a suitable slot 36 in the bottom of the guide block 19. This lever 33 is pivoted in a suitable recess 37 in the top of the handle portion of the tool. The pivot 38 for this lever 33 is also used to provide additional means for securing the half sections 11 together. The hole 34 is sufficiently large to allow the movement of the lever 33 to a full stroke toward the fixed jaw face 17 for moving the guide block 19 and jaw 24 far enough to bring the gripping face 26 of the jaw 24 into contact with the gripping face 17 of the fixed jaw 16.

The bottom 39 of the cavity 29, is parallel with the top of the guide block 19 and is at right angles to the planes of the gripping faces 17 and 26. A side opening 41 is provided between the massive flanges 32 and the top of the handle portion. A wedge block 42 is placed in the bottom of the cavity 29. This wedge block 42 has a bottom 43 which rides on the bottom wall 39 of the cavity 29. The top 44 of the wedge block 42 is inclined parallel with the tapered edge 22 of the guide block 19. The wedge block is so located in the cavity 29 that its shorter end 46 is opposite the opening 41 and its larger end 47 is adjacent to, but does not touch the lever 33. A socket 48 extends from the larger end 47 of the wedge block 42 toward the shorter end 46, but it does not extend entirely through the block. Inside of this socket 48 is a plunger 49, the abutment head 51 of which abuts against the lever 33. A coil spring 52 is positioned around the stem of the plunger 49 and bears at one end against the bottom of the socket 48, and at its other end against the abutment head 51 so as to urge the abutment head 51 against the lever 33.

Inside of the cavity 29 and between the guide block 19 and the wedge block 42, is a spacer or locking block 53. The ends of this locking block 53 are tapered parallel with each other and with the tapered edge 22 of the guide block 19 and the tapered top 44 of the wedge block 42. The length of the locking block 53 is such that it is in constant engagement with the respective sides of the guide block 19 and wedge block 42. The sides of the locking block 53 are parallel with the longitudinal axis of the tool and in this illustration also with the planes of the gripping faces 17 and 26. One side of the locking block 53 is in slidable contact with the inner faces of the massive flanges 32. The opposite side or edge of the locking block 53 is in slidable contact with a guide 54 secured in the cavity 29. In this manner movement of the locking block 53 is limited to reciprocation longitudinally of the tool and in this form on a path parallel with the planes of the jaw gripping faces 17 and 26.

In operation, the opening between the jaw faces 17 and 26 is adjusted by pushing the lever 33 inward of the opening 34. It is to be noted that a substantial portion of the lever 33 is exposed

between its pivoted end and the hole 34 so as to allow an easy gripping of the tool and an easy engagement by one hand for pressing the lever 33 inwardly of the cavity 29. This pushing of the lever 33 causes the movement of the guide block 19 and the jaw 24 therewith toward the fixed jaw 16. At the same time the wedge block 42 is also moved in the same direction. The locking block 53 is engaged with the inclined side 22 of the guide block 19 and with the inclined top 44 of the wedge block 42 and it is forced to move upwardly or toward the jaws of the tool. When the jaw 24 reaches the desired adjustment and engages the object, such as a nut, then the force that is exerted on the jaw 24 tending to pry it away from the jaw 16, is resisted by the wedging engagement of the inclined face 22 of the guide block 19 with the top of the locking block 53 which latter, in turn, is pressed against the inclined top 44 of the wedge block 42. This engagement is entirely fixed and prevents any outward movement of the jaw 24 until such time that the wedge block 42 is pushed back toward the lever 33. It is to be noted that the top of the lever 33 must travel a longer distance than the portion of the lever 33 opposite the wedge block 42. The wedge block 42, however, is advanced in the same proportion as the guide block 19 by the action of the plunger head 51 on the coil spring 52, which latter in turn forces the wedge block 42 to move to the degree required to remain in contact with the locking block 53.

In order to release the grip on the object, the operator pushes the short end of the wedge block 42 so that the wedge block 42 is moved toward the lever 33, thereby allowing the downward motion of the locking block 53 and the corresponding outward horizontal motion of the guide block 19, so as to carry the jaw 24 toward its outer position. Wherever the wedge block 42 is stopped it positively holds the opening between the jaw faces 17 and 26, thereby providing a positive and quick control of the gripping distance between the jaw faces in all positions.

In general, in all the forms of my invention all the necessity for tedious adjustment for gripping and releasing of the wrench by screws, worms and the like is entirely eliminated. The respective jaws of the gripping tools of my invention can be initially adjusted very quickly by one motion to approximately the size of the object to be gripped with just sufficient clearance to allow the placing of the tool upon the object. Then by another simple motion, which can be accomplished by the gripping hand of the operator, the jaws are firmly locked upon the object and loosening of the tool from the object is positively prevented. In manipulating the tool on the object, the same can be loosened by a simple motion sufficiently to reposition the tool for the next grip and then by a very slight motion of the handles or the wedge block the jaws can be firmly locked again on the object for the next manipulation. This tool permits a positive and firm engagement with the object without any clearance or looseness, and at the same time it permits an easier and quicker operation of quickly repeated grips, as are frequently needed in operations with wrenches and pliers. Both the preliminary adjustment and the final gripping can be accomplished with one hand and each in one step. The principle and the mechanism involved for the jaw adjustment is simple; it can be readily adapted for the various types of tools,

and results in higher efficiency and speed of operations with such tools.

I claim:

1. In a gripping tool of the character described, a tool body, an adjustable jaw support comprising a jaw base movable on the tool body to carry a jaw thereon to adjusted positions, a wedge member on the tool body opposite the jaw base, the edges of said wedge member and of said jaw base facing one another and being inclined at substantially parallel angles, an element held between said inclined edges of said wedge member and said jaw base in compression and being reciprocable so as to transmit forces from the jaw face to the wedge at such angle as to prevent movement of said jaw from its adjusted position, means to simultaneously adjust the jaw base, and said element on and by the wedge so as to move the jaw to selected openings, means to maintain said element in constant contacting relation with said inclined edges of said jaw base and said wedge member, and means to guide the jaw base so as to hold the jaw gripping face at a constant angle in all of its adjusted positions.

2. In a gripping tool of the character described a tool body, a movable jaw base on said body, a jaw on said base adjusted by the positioning of said jaw base to selected jaw openings, means on the body to guide said jaw base so as to hold said jaw at constant angle with respect to said tool body, a movable wedge in said body, said jaw base having an inclined side opposite to and spaced from said wedge, an element held in compression between said inclined side of the base and said wedge and being reciprocable in said body, and means to simultaneously move said wedge, said jaw base and said reciprocating element for adjusting the jaw opening and for holding said jaw in said adjusted positions.

3. In a gripping tool of the character described the combination with a tool body having a handle and a fixed jaw, a movable jaw base on the body, a jaw held by the movable jaw base opposite said fixed jaw, means to guide said movable jaw base on the body so as to maintain the movable jaw substantially parallel with the fixed jaw, an adjustable wedge in the body spaced from the movable jaw base, an inclined side of said wedge facing toward said jaw base, the side of the jaw base facing toward said wedge being inclined substantially parallel with said inclined side of said wedge, an element having inclined ends in constant contact with said inclined sides, means to guide said element for reciprocation at substantially right angles to the direction of movement of said wedge, and means for moving said wedge and said jaw base simultaneously and in the same direction.

4. In a gripping tool of the character described, a body and handle formed of complementary superimposed sections, said sections being recessed on their opposed surfaces to form a hollow tool body, a fixed jaw formed on said body, a movable jaw support adjustable through the interior of the hollow body toward to and away from the plane of the face of said fixed jaw, a jaw on said jaw support opposite the fixed jaw, means in the hollow body to guide said movable jaw support so as to hold said movable jaw substantially in parallelism with said fixed jaw, the edge of said jaw support inside said body being inclined with respect to the direction of motion of said jaw support, a wedge member movable through the hollow body substantially parallel with the movement of the jaw support, an inclined edge of said

wedge member being substantially parallel with the inclined edge of said movable jaw support, an element between said inclined side and inclined edge, means to hold said element for reciprocation on a path substantially at right angles to the path of movement of said support and said wedge, the ends of said element being inclined parallel with each other and with said inclined side and edge and in constant contact therewith, an element engageable with said jaw support for moving said jaw support, and abutment means between said last element and said wedge for moving said wedge simultaneously with and to the same extent as said jaw support.

5. In a gripping tool of the character described, the combination with the tool body having a handle at one end and a jaw at the other end thereof, of a pair of spaced members movable in said body in the same direction and transversely to the plane of the face of said jaw, one of said members carrying a second jaw in opposite operative relation to the first jaw, the edges of said members facing toward each other being inclined in the same direction, an element between said spaced members held in said body for reciprocation on a path at a constant angle to the direction of movement of said members; the opposite ends of said reciprocating element being in constant contact with the opposed inclined edges of said members so as to hold the said jaw carrying member against any movement relatively to the other movable member, and means for simultaneously applying a moving force to both of said members for adjusting the opening between said jaws.

6. In a gripping tool of the character described the combination with the tool body having a handle at one end and a jaw at the other end thereof, of a pair of spaced members movable in said body in the same direction and transversely to the plane of the face of said jaw, one of said members carrying a second jaw in opposite operative relation to the first jaw, the opposed edges of said members being inclined in the same direction, an element between said spaced members held in said body for reciprocation on a path at a substantially constant angle to the direction of movement of said members; the opposite ends of said reciprocating element being in constant contact with the opposed inclined edges of said members so as to hold the said jaw carrying member against any movement relatively to the other movable member, a lever pivoted on the tool body and connected to the jaw carrying member for moving said jaw carrying member to adjusted positions, and means between said lever and the other member for simultaneously imparting motion to said other member to the same extent as the adjusting movement of said jaw carrying member.

7. In a gripping tool of the character described the combination with the tool body having a handle at one end and a jaw at the other end thereof, of a pair of spaced members movable in said body in the same direction and transversely to the plane of the face of said jaw, one of said members carrying a second jaw in opposite operative relation to the first jaw, the opposite edges of said members being inclined in the same direction, an element between said spaced members held in said body for reciprocation on a path at a substantially constant angle to the direction of movement of said members; the opposite ends of said reciprocating element being in constant contact with the opposed inclined edges of said mem-

bers so as to hold the said jaw carrying member against any movement relatively to the other movable member, a lever pivoted in the handle of the tool and connected to said jaw carrying member whereby a moving force can be imparted to said jaw carrying member, an engagement element movable in said other member, a spring in said other member urging said engagement element against said lever, the force of said spring being such that it moves said other member to the extent permitted by the adjustment movement of the jaw carrying member.

8. In a gripping tool of the character described the combination with the tool body having a handle at one end and a jaw at the other end thereof, of a pair of spaced members movable in said body in the same direction and transversely to the plane of the face of said jaw, one of said members carrying a second jaw in opposed operative relation to the first jaw, the opposite edges of said members being inclined in the same direction, an element between said spaced members held in said body for reciprocation on a path at a substantially constant angle to the direction of movement of said members; the opposite ends of said reciprocating element being in constant contact with the opposed inclined edges of said members so as to hold the said jaw carrying member against any movement relatively to the other movable member, a lever pivoted in the handle of the tool and connected to said jaw carrying member whereby a moving force can be imparted to said jaw carrying member, an engagement element movable in said other member, a spring in said other member urging said engagement element against said lever, the force of said spring being such that it moves said other member to the extent permitted by the adjustment movement of the jaw carrying member, said lever being pivoted between said other member and the handle of the tool.

9. In a gripping tool of the character described the combination with the tool body having a handle at one end and a jaw at the other end thereof, of a pair of spaced members movable in said body in the same direction and transversely to the plane of the face of said jaw, one of said members carrying a second jaw in opposite operative relation to the fixed jaw, the opposed edges of said members being inclined in the same direction, an element between said spaced members held in said body for reciprocation on a path at a substantially constant angle to the direction of movement of said members; the opposite ends of said reciprocating element being in constant contact with the opposed inclined edges of said members so as to hold the said jaw carrying member against any movement relatively to the other movable member, and means for simultaneously applying a moving force to both of said members for adjusting the opening between said jaws, said tool body being hollow and said members and said element between said members being guided within the cavity of the hollow body.

10. A wrench comprising a pair of superposed sections secured together to form the body, the handle and a fixed jaw of the wrench, the overlying faces of said sections in the body portion of said wrench being hollow so as to form a cavity in the wrench, a jaw carrying block, a jaw extended from said block opposite to and in operative relation to the fixed jaw and being movable in said cavity so as to adjust the position of the jaw carried thereby with respect to the fixed jaw to selected wrench openings, means to guide

said carrying block on a predetermined path, a wedge block in said cavity of the tool body being spaced from the jaw carrying block, the inclined side of the wedge block facing toward said carrying block, the side of said carrying block opposite said wedge block being inclined in substantial parallelism with the inclined side of the wedge block, a compression element in said cavity in constant engagement with the parallel sides of said jaw carrying block and said wedge block being confined to reciprocating movement at a constant angle to the direction of the adjusting movements of said blocks and in accordance with the simultaneous movements of said inclined sides of the blocks, a hand lever pivoted in the handle and extended into said cavity, said hand lever being connected to said jaw carrying block for moving the same according to the manual forces exerted on said hand lever, a spring in the wedge block, an abutment pressed by said spring against said hand lever so that said spring is held under such compression as to equalize the movement of the wedge block with the adjusting movements of the jaw carrying block, said tool body having an opening on its edge opposite said hand lever and at said wedge block to permit said wedge block to protrude beyond said edge of the tool body when said hand lever and said jaw carrying block are moved toward the fixed jaw, said protruding end of said wedge block being engageable by hand for moving the wedge block and said hand lever in

11. A wrench comprising a pair of superposed sections secured together to form the body, the handle and a fixed jaw of the wrench, the overlying faces of said sections in the jaw portion of said wrench being hollow so as to form a cavity in the wrench, a jaw carrying block, a jaw extended from said block opposite to and in operative relation to the fixed jaw and being movable in said cavity so as to adjust the position of the jaw carried thereby with respect to the fixed jaw to selected wrench openings, means to guide said carrying block on a predetermined path, a wedge block in said cavity of the tool body being spaced from the carrying block, the inclined side of the wedge block facing toward said carrying block, the side of said carrying block opposite said wedge block being inclined in substantial parallelism with the inclined side of the wedge block, a compression element in said cavity in constant engagement with the parallel sides of said carrier block and said wedge block and being confined to reciprocating movement at a constant angle to the direction of adjusting movements of said blocks and in accordance with the simultaneous movements of said inclined sides of the blocks, a lever pivoted in the handle and extended into said cavity, said lever being connected to said jaw carrying block for moving the same according to the manual forces exerted on said lever, a spring in the wedge block, an abutment pressed by said spring against said hand lever so that said spring is held under such compression as to equalize the movement of the wedge block with the adjusting movements of the jaw carrying block, said tool body having an opening on its edge opposite said hand lever and at said wedge block to permit said wedge block to protrude beyond said edge of the tool body when said hand lever and said jaw carrying block are moved toward the fixed jaw, said protruding end of said wedge block being engageable by hand for moving the wedge block and said hand lever in

a direction to move the jaw carrying block away from said fixed jaw, and means to limit the movement of said jaw carrying block outward away from the fixed jaw to the largest wrench jaw opening.

12. A wrench comprising a pair of superposed sections secured together to form the body and handle and a fixed jaw of the wrench, the overlying faces of said sections in the body portion of said wrench being hollow so as to form a cavity in the wrench, a jaw carrying block, a jaw extended from said block opposite to and in operative relation to the fixed jaw and being movable in said cavity so as to adjust the position of the jaw carried thereby with respect to the fixed jaw to selected wrench openings, a wedge block in said cavity of the tool body being spaced from the carrying block, the inclined side of the wedge block facing toward said carrying block, the side of said carrying block opposite said wedge block being inclined in substantial parallelism with the inclined side of the wedge block, a compression element in said cavity in constant engagement with the parallel sides of said carrier block and said wedge block and being confined to reciprocating movement at a constant angle to the direction of adjusting movements of said blocks and in accordance with the simultaneous movements of said inclined sides of the blocks, a hand lever pivoted in the handle and extended into said cavity, said hand lever being connected to said jaw carrying block for moving the same according to the manual forces exerted on said hand lever, a spring in the wedge block, an abutment pressed by said spring against said hand lever so that said spring is held under such compression as to equalize the movement of the wedge block with the adjusting movements of the jaw carrying block, said tool body having an opening on its edge opposite said hand lever and at said wedge block to permit said wedge block to protrude beyond said edge of the tool body when said hand lever and said jaw carrying block are moved toward the fixed jaw, said protruding end of the wedge block being engageable by hand for moving the wedge block and said hand lever in a direction to move the jaw carrying block away from said fixed jaw, opposite guide projections in the cavity alongside the path of said jaw carrying block, and said jaw carrying block having guide grooves thereon travelling on said guide projections.

13. A wrench comprising a pair of superposed sections secured together to form the body, the handle and a fixed jaw of the wrench, the overlying faces of said sections in the body portion of said wrench being hollow so as to form a cavity in the wrench, a jaw carrying block, a jaw extended from said block opposite to and in operative relation to the fixed jaw and being movable in said cavity so as to adjust the position of the jaw carried thereby with respect to the fixed jaw to selected wrench openings, a wedge block in said cavity of the tool body being spaced from the carrying block, the inclined side of the wedge block facing toward said carrying block the side of said carrying block opposite said wedge block being inclined in substantial parallelism with the inclined side of the wedge block, a compression element in said cavity in constant engagement with the parallel sides of said carrying block and said wedge block being confined to reciprocating movement at a constant angle to the direction of adjusting movements of said blocks and in accordance with the simultaneous movements of said inclined sides of the blocks, a hand lever pivoted in the handle and extended into said cavity, said hand lever being connected to said jaw carrying block for moving the same according to the manual forces exerted on said hand lever, a spring in the wedge block, an abutment pressed by said spring against said hand lever so that said spring is held under such compression as to equalize the movement of the wedge block with the adjusting movements of the jaw carrying block, said tool body having an opening on its edge opposite said hand lever and at said wedge block to permit said wedge block to protrude beyond said edge of the tool body when said hand lever and said jaw carrying block are moved toward the fixed jaw, said protruding end of the wedge block being engageable by hand for moving the wedge block and said hand lever in a direction to move the jaw carrying block away from said fixed jaw, opposite guide projections in the cavity alongside the path of said jaw carrying block, said jaw carrying block having guide grooves thereon travelling on said guide projections, and means to align and hold together the said sections forming the body and handle of said tool.

JOHN B. ZIMDARS.
